(57) **CLAIM**

The ornamental design for a set of connectors, as shown and described.

DESCRIPTION

FIG. 1 is a front, right, top perspective view of a set of connectors showing the new design, in a plugged configuration;

FIG. 2 is a rear, left, bottom perspective view thereof; FIG. 3 is a front, bottom perspective view of the set of connectors showing the new design, in an unplugged configuration;

FIG. 4 is a rear, top perspective view thereof;

FIG. 5 is a top, front perspective view thereof of a female connector of the set;

FIG. 6 is a rear, bottom perspective view thereof;

FIG. 7 is a front elevation view thereof;

FIG. 8 is a rear elevation view thereof;

FIG. 9 is a right side view thereof;

FIG. 10 is a left side view thereof;

FIG. 11 is a top plan view thereof;

FIG. 12 is a bottom plan view thereof;

FIG. 13 is a top, front perspective view thereof of a male connector of the set;

FIG. 14 is a rear, bottom perspective view thereof;

FIG. 15 is a front elevation view thereof;

FIG. 16 is a rear elevation view thereof;

FIG. 17 is a right side view thereof;

FIG. 18 is a left side view thereof;

FIG. 19 is a top plan view thereof; and,

FIG. 20 is a bottom plan view thereof.

The broken lines of even-length shown in the drawings illustrate portions of the set of connectors that form no part of the claimed design.

1 Claim, 20 Drawing Sheets
